UNITED STATES PATENT OFFICE.

EDWIN A. HALLAM, OF PORTLAND, OREGON.

DRYING-KILN.

1,119,595.

Specification of Letters Patent.

Patented Dec. 1, 1914.

Application filed February 25, 1914. Serial No. 530,871.

To all whom it may concern:

Be it known that I, EDWIN A. HALLAM, a citizen of the United States, residing at Portland, in the county of Multnomah and 5 State of Oregon, have invented new and useful Improvements in Drying-Kilns, of which the following is a specification.

This invention relates to improvements in drying kilns, and proposes a construction 10 which is more especially applicable to the drying of lumber and is directed to the same principles of operation which are incident to the construction shown in my prior Patent No. 1,067,110, of July 8, 1913, the construction proposed by the present invention being in the nature of an improvement upon the construction shown in my said prior patent.

The object of the present invention is to 20 provide a construction which secures all of the advantages secured by my prior construction, and enumerated in the specification of my said prior patent, and which, in addition, is simpler in its structural details, 25 less expensive to install, better adapted for kiln rooms having relatively high ceilings and wherein the stacks of lumber are of relatively great height, and produces a product of superior quality by a drying operation 30 of expeditious character.

According to the present invention, pipes or equivalent devices are arranged adjacent the side walls of the kiln room, extending longitudinally of said room, and are provided on their under sides with openings through which steam is discharged in the form of downwardly delivered jets having considerable intensity. The jets of steam are directed downwardly at such an angle 45 that they do not directly act on the sides of the stack, but on the contrary, pass through the skeleton walk way to the space under the heaters and induce the downward circulation of air at the sides of the stack, the air thus caused to circulate downwardly thoroughly taking up or mixing with the steam and passing through and over the heaters into the central portion of the stack, through which it rises uniformly. The air which 50 circulates downwardly at the sides of the stack and takes up the steam which induces such downward circulation reduces the temperature of the steam, and that portion of the moisture-laden air which rises over the heater or the heating coils reduces to some

extent the heat which rises from said coils. These reductions in the heat of the steam and in the heat of the air which rises from the heaters or heating coils are beneficial, in that they in no way retard the drying operation, but on the contrary, eliminate those detrimental effects, such as "case hardening" of the lumber, which are caused by the more or less direct application of too great a degree of heat to the stack which is to be 60 dried. The elevation of the pipes at the sides of the stack which deliver the downward jets of steam is immaterial, except that it must be selected to provide for a proper downward circulation of the air at the sides 65 of the stack, and also to prevent sufficient moisture from being suspended in the air which rises from the heaters to have any retarding effect on the drying operation. It has been found by actual practice that an 70 elevation of the steam pipes which serves both of the conditions stated can be readily determined.

A drying kiln in which the features of the invention are incorporated is illustrated in 75 the accompanying drawings, wherein:

Figure 1 is a transverse sectional view of a single track kiln; Fig. 2 is a vertical longitudinal sectional view thereof; and Fig. 3 is a plan view of a portion of the 80 floor of the kiln at one side thereof.

Similar characters of reference designate corresponding parts in all of the views.

The kiln room may be of any desired or improved construction. The drying trucks 85 1 move on rails 2 supported by stringers 3, and in the space between the rails, at a suitable distance below the trucks, there are arranged the usual radiators or heating coils 4. The lumber is stacked in any suitable 90 manner on the trucks. Between the sides of the stack and the side walls of the kiln room are spaces 5 which are utilized as walk ways, such walk ways having floors 6. The spaces 5 are also utilized as circulation passages, 100 and the air which is utilized in the drying operation circulates downwardly through the walk ways 5 and under the heating coils 4. The floors 6 may be of any suitable construction, except, of course, that openings 105 or spaces must be provided through which the air may pass in its downward circulation. For example, these floors may be made up of transverse beams arranged in spaced relation, either without any covering of 110

flooring boards or with a partial covering of flooring boards.

The downward circulation of air through the walk ways is induced by downwardly directed jets of steam which are discharged by horizontal pipes or equivalent steam conducting devices 7. The pipes 7 are arranged adjacent the side walls of the kiln room and are provided on their under sides with steam discharge openings or nozzles 8. The spacing of the pipes 7 from the sides of the stack, and the angle of the discharge openings or nozzles, is selected whereby the steam which is discharged in jets of considerable intensity from said pipes is directed downwardly in such manner that it passes through the floors 6 and in relation to the heaters 4, without having any substantial direct action on the lumber. The air which is caused to circulate downwardly by the downwardly directed jets of steam uniformly mixes with said steam, and the steam or moisture-laden air passing under the floors 6 circulates in relation to the coils 4, some of the air passing under and upwardly through these coils, and some of the air passing directly over these coils. The air which passes over the coils 4 reduces to some extent the heat which rises from the coils, not sufficiently to retard the drying operation, but with beneficial effect, in that it eliminates any liability of "case hardening" of the lumber. The heated air rising from the coils 4 and having a percentage of moisture incorporated therein, passes into the central portion of the stack and rises through the stack uniformly throughout the width thereof and with substantially uniform drying effect. The drying of the lumber is due, for the most part, to the circulation of air at the sides of the stack, since such downwardly

circulating air retains a substantial degree of heat.

The improvement herein described may be used in connection with a steam pipe 9 arranged above the stack for introducing moisture into the air and serving the purpose of the pipe 10 disclosed in my prior Patent No. 1,067,110, above referred to. The steam pipe 7 may be used in lieu of the shields 5 shown in my prior patent just referred to.

Having fully described my invention, I claim:

In a drying kiln, a kiln room, heaters for the air arranged below the stack to be dried, the kiln room having walk ways at the sides of the stack, the walk ways having skeleton floors, and steam pipes arranged adjacent the sides of the kiln room and in said walk ways, said steam pipes having openings along their underside through which jets of steam are delivered downwardly, the downward jets of steam inducing a downward circulation of air through the walk ways and causing the downwardly circulating air to pass through the skeleton floors and in relation to said heaters, the steam pipes being so located relatively to the stack of lumber that the steam, in its downward circulation, has no direct drying effect on the said lumber and being so located relatively to the heaters that the moisture introduced thereby into the air has no retarding effect on the drying operation.

In testimony whereof I have hereunto set my hand in presence of two subscribing witnesses.

EDWIN A. HALLAM.
